KATHARINE OHLER, OF LOS ANGELES, CALIFORNIA

COMBINATION INKSTAND AND PENWIPER

Application filed June 29, 1927. Serial No. 202,378.

My invention is a combination ink stand and pen wiper in which an ink bottle is held in a stand and a pen wiper is incorporated with the lid of the stand.

An object of my invention is the construction of a combination ink stand and pen wiper in which an ink bottle may be inserted and clamped or locked in a stand which may be of any suitable shape. This stand is provided with a hinged or removable lid to which is secured a pen wiper, the pen wiper being positioned to form a cover for the open neck of the bottle when the lid is closed, and thus preserve the ink from dirt, leakage and evaporation.

Another object of my invention is the construction of a combination stand in which the base of the stand is hinged to the wall or body or removably clamped thereto so that an ink bottle may be inserted in the stand with the base open, and the neck thrust upwardly through an opening in a horizontal partition. The bottle may then be held in place by a finger while the base is hinged. If the base is separate the bottle may be placed therein and the stand fitted over the base and bottle. This construction provides a container which holds a much larger quantity of ink than is usually provided, thus avoiding continual refilling.

My invention is illustrated in the accompanying drawings, in which:

Figure 1 is a perspective view of my invention with the lid tilted up showing the ink stand in position for usage.

Figure 2 is a vertical section diametrically through the center of the ink stand from the back to the front.

Figure 3 is a horizontal section taken on the line 3-3 of Fig. 2, in the direction of the arrows.

Figure 4 is a section similar to Fig. 2 showing the manner of inserting the bottle.

Figure 5 is a detail section of an alternative connection of the base to the body or walls of the ink stand.

In constructing my invention I utilize a base 11 which may be a flat sheet of metal or wood and having a flange 12 extending around the front and both sides. It is pref-

erable to have the flange slightly lower at the front than the sides, as indicated by the numeral 13. There may be two flanges, one on either side, but not in front. The body or walls of the stand are indicated by the numeral 14 and in the illustration the stand is shown as being rectangular, but it is to be understood that it may be made of any other suitable shape. The base is preferably secured to one of the walls by hinges 15 which may be of any suitable character and attaches to the front wall by means of a spring clip 16, or other equivalent device, which engages in a notch 17 formed on the front wall.

A horizontal partition 18 may be secured to the side walls with an opening 19 therethrough. The walls have an upper extension 20 above this horizontal partition 18, providing a pen wiper chamber 21, the lower part of the ink stand forming a bottle chamber 22 in which an ink bottle 23 may be placed with the neck 24 extending through the opening 19 in the partition.

A lid 25 is secured to the upper extension of the walls by hinges 26 and secured to the center of the lid on the inside there is a screw-threaded socket 27 in which is threaded a screw 28, this screw having a head 29 with a washer 30 thereunder.

A pen wiper, designated generally by the numeral 31, has a plurality of layers of fabric 32, each layer being of diminishing diameter from the layer next the lid of the outermost layer. Each of these layers has a central opening 33 therethrough so that the layers may fit on the outside of the socket 27 and have the screw 28 pass through these holes or openings. The washer 30 or the outermost pen wiper layer engages underneath the head of the screw and thus all the layers are securely clamped in position. The pen wiper may also be secured simply by a pin having a large head. Each of the layers has a scalloped edge 34 to facilitate wiping the pens. A clasp of any suitable character 35 is utilized to secure the lid to the front wall of the ink stand and thus complete the closure. The under side of the pen may be cleaned by wiping on the edges of the discs and the upper side on the surfaces. This

pen wiper is placed in the most convenient position for use, being held vertically when the lid is raised, and cannot be misplaced or lost.

5 In the construction illustrated in Fig. 5, the base 36 has a flange 37 thereabouts and has a plurality of spring clips 38 which engage in notches 39 in the walls 40 so that by this construction the base may be connected to the walls by a straight reciprocating movement; the base and the body of the ink stand being held by the clips.

10 The manner of manipulating the ink stand, Figs. 1 through 4, is substantially as follows:

15 My stand is preferably made of such character that the small commercial bottles of ink may be inserted therein. After removing the stopper from a bottle of this character, it may be inserted upwardly in the ink stand body, by unclasping the base and allowing it to hinge downwardly, as shown in Figs. 2 and 4. With one or more fingers the bottle may be held pressed up against the 20 partition 18 and the base closed until it engages the bottom of the bottle. The finger may then be withdrawn and the base forced upwardly until it is secured by the clasp.

25 It will be noted by my construction that when the lid is closed, as shown in Fig. 2, the pen wiper drops over the top of the bottle neck and thus forms a closure for such bottle neck, preventing dirt from getting into the bottle and, to a great extent, preventing evaporation and leakage, thus it is not necessary to replace the cork in the bottle.

30 In the construction of Fig. 5 the base and the walls may be separated and the bottle placed between the flanges 37 and then the wall structure forced downwardly on the base and secured in position by the spring clips. It is to be understood that in both 35 constructions the flange on the base functions to center the bottle.

40 While I have illustrated my invention as a simple design and without ornamentation, it is to be understood that the shape may be changed to be more complex and the design to be as ornamental as desired. The ink stand may be made also to contain two or 45 more bottles, to provide different colors or qualities of ink.

50 Various changes may be made in the principles of my invention without departing from the spirit thereof, as set forth in the 55 description, drawings and claims.

I claim:

55 1. An ink stand and pen wiper combination comprising an ink stand adapted to receive a bottle therein, a lid having a stud secured thereto and a screw threaded in said stud, a plurality of layers of fabric mounted on the stud and the screw, forming a pen wiper, said pen wiper covering the neck of a bottle 60 within said stand when the lid is closed.

2. A pen wiper comprising in combination a support, a tubular structure forming a socket connected thereto, a headed screw threaded in said socket, a plurality of layers of fabric, each having an opening through which said socket structure extends, and said screw detachably securing the layers of fabric in position.

70 3. In an ink stand structure, a container for a reservoir open at the top, a cover for said container, and a pen wiper comprising a plurality of layers and means for securing the center portions of said layers to the under side of said cover, whereby the edges of said layers are draped over the open top of said reservoir when the cover is closed.

75 In testimony whereof I have signed my name to this specification.

KATHARINE OHLER.
